WATER MOTOR

Filed April 25, 1922

Patented Mar. 17, 1925.

1,529,824

UNITED STATES PATENT OFFICE.

WILLIAM ADELMANN, OF NEW YORK, N. Y.

WATER MOTOR.

Application filed April 25, 1922. Serial No. 556,368.

To all whom it may concern:

Be it known that I, WILLIAM ADELMANN, a citizen of the United States, residing at the city of New York, borough of the Bronx, 5 in the county of Bronx and State of New York, have invented certain new and useful Improvements in Water Motors, of which the following is a specification.

This invention relates to water power appliances and has particular reference to a construction including a member adapted to be rotated constantly around a horizontal axis by the weight and force of a current of water flowing thereover or caused to 15 fall upon the side thereof remote from the source of the flow or supply of water.

While I am aware that various types of water wheels have been proposed heretofore, none that have been brought to my attention have possessed the adaptability for 20 erection and operation in any suitable or desired spot in a river or other current of water without the expenditure of a considerable amount of money in the erection of 25 a dam. One of the objects of the improvement therefore is to provide a construction of a strong durable nature adapted to be easily built in or along any stream and with the necessity for practically no dam construction except as will be set forth more 30 fully below.

Another object of the invention is to provide a water motor adapted for continuous operation and development of power not 35 only day and night but throughout the full twelve months of the year irrespective of the condition of the stream with respect to ice or other materials supported or floating on the surface of the water. In other words, 40 one of the chief objects of the invention is to provide a water power mechanism which will be of constant adaptability for power and which will be "fool proof", requiring never more than a minimum amount of attention to keep it in running order.

A still further object of the invention is to provide a water power plant so designed 45 as to possess the highest possible percentage of efficiency in proportion to the amount of water flowing along the stream.

With the foregoing and other objects in view the invention consists in the arrangement and combination of parts hereinafter described and claimed, and while the invention 55 is not restricted to the exact details of construction disclosed or suggested herein,

still for the purpose of illustrating a practical embodiment thereof reference is had to the accompanying drawings, in which like reference characters designate the same parts in the several views, and in which—

Figure 1 is a plan view.

Fig. 2 is a vertical section on the line 2—2 of Fig. 1.

Fig. 3 is a vertical section on the line 3—3 of Fig. 2.

Fig. 4 is an enlarged detail of the bridge mechanism.

Fig. 5 is a plan view indicating a modification.

Referring now more specifically to the drawings 10 indicates the bed of any convenient stream whose normal banks may be understood to be at 11. The site for the machine having been determined suitable 15 permanent buttresses 12 of concrete, or its equivalent, are erected from a suitable depth below the bed of the stream and along the banks thereof and extending to a suitable elevation, say eight or ten feet above the 20 bed of the stream, and extending parallel to the stream. Fitted in these buttresses are a pair of bearings 13 and 14 at an elevation of say about four feet, more or less, and with their axes in transverse horizontal alignment. Extending up the stream as continuations of the buttresses are suitable retaining walls 15 of a height approximating that of the buttresses and carried substantially level along their upper edges far 25 enough up the stream to produce a head of water for the operation of my motor. The length of these retaining walls up the stream will naturally depend upon the amount of fall found in the bottom of the stream at 30 the place selected.

Built in or supported in any convenient manner upon or between the buttresses is a girder 16. This member extends across the stream between the buttresses and is 35 made of angle metal or its equivalent with sufficient stiffness and strength to support the members carried thereby, as fully set forth below. If the stream is sufficiently wide this girder may demand intermediate 40 supports of concrete or the like, but for a span of from ten to fourteen or sixteen feet no intermediate supports are ordinarily necessary.

As shown in the main figures the wheel 110 or rotor 17 is composed of a plurality of sections 18, each of, say for example, six

feet in diameter and eight feet in length and comprising a solid core or center 19 and a circular series of concave blades or buckets 20. Also each section has closed 5 ends 21 of disk shape. A gudgeon 22 is secured to the center of one end of the first section and has bearing in the bearing cup 13. The several sections are secured together end to end by means of fastening 10 members 23 passing through registering holes in the adjacent disks 21. The remote end of the opposite section has connected to its center a power shaft 24 which has bearing in the bearing sleeve 14 and from 15 which shaft the power may be taken as from a pulley 25 or its equivalent. Thus the rotor will be of unitary construction and substantially integral throughout and supported only at its ends. When however the 20 stream is too wide for the rotor to be supported only at its ends I may provide one or more intermediate buttresses 12', as in Fig. 5, and in which auxiliary shafts 24' may be journaled. Otherwise the connections 25 between the parts of the rotor may be the same as above outlined. It will of course be noted that the buckets 20 on the effective or down stream side of the axis of the rotor are bent upward. By constructing 30 the wheel or rotor of a plurality of sections arranged end to end, the several sections may be made of standard lengths or sizes, and for the erection of a motor in any particular place according to the width 35 of the stream or the amount of available power, it is expedient to employ and assemble any desired number of such standard sections, a result that is readily accomplished by reason of the construction of 40 the sections, with their own independent sets of blades or buckets and with standard end fastening means.

The girder 16 is provided along its upper edge with a rabbet 26 in which are received 45 the ends of a series of stringers 27 arranged parallel to one another and resting with their other ends at or upon the bottom of the stream on the up stream side of the machine, the stringers being given an inclination 50 suitable for directing the water or materials floating on the water up and over the girder. To effect this action I provide transverse planks 28 which may be of heavy 55 oak or other durable species of wood while the stringers may be of metal, such as I-beams. These stringers may easily be put in place and fastened if desired to the girder and then the planks 28 are put in place 60 transversely of the stringers, making a substantially water tight bridge over which the water will flow.

29 indicates an adjustable coping supported at its up stream edge upon or near the top of the girder, the upper surface 65 of the coping lying substantially flush with

the upper surface of the uppermost plank 28. Any suitable means however such as shown at 30 may be arranged to adjust and variably support the free edge of the coping, whereby the same may be held close 70 to or more remote from the top of the rotor 17.

With the device erected as set forth and with the coping adjusted at a suitable level corresponding to the depth of the water, 75 the velocity of the current, or other local conditions, the water flowing thereover and falling upon the down stream side of the rotor will fill the buckets on such side and the force of the stream and the weight of the water in the buckets will cause a rotation of the rotor as indicated by the arrow. This rotation of the rotor will be continuous, according to the continuity of the current, day and night and throughout the 80 seasons. Any floating materials such as cakes of ice, logs, or the like, will pass over along with the water and will have no other effect upon the rotor than to insure rotation thereof as intended. No breakage or 85 other damage to the rotor can result from such materials. Obviously the power taken off at the pulley or gear wheel 25 may be transmitted to any desired distance and used for any desirable purpose. Because of the 90 continuity of the power the efficiency of the machine will be relatively high even though the power developed in any unit of time may be only moderate, although in most 95 installations the power will be ample for 100 the driving of heavy machinery such as dynamos or other power storing or generating mechanism.

I claim:

1. A water wheel comprising a plurality 105 of co-axial rotor sections each of which comprises a pair of co-axial end stiffening flanges, a central solid core for each section connecting said flanges, and a plurality of blades connecting with said flanges and said core, said blades, said core and said flanges forming an integral rotor section, bolt means passing through the abutting flanges between adjacent blades and connecting said abutting flanges of the adjacent rotor sections directly each to each, and bearing and supporting means fixed to the remote ends only of the rotor.

2. In a device of the character set forth, the combination of a pair of spaced parallel 120 concrete buttresses having bearing members built therein, a rotating member journaled in said bearing members and substantially of a length filling the space between the buttresses, the rotating member being of unitary structure and comprising rigid buckets upwardly curved on the down stream side of the axis thereof, and bridge mechanism serving to cause the water to flow in a continuous unobstructed stream over the top of 125 130

the rotating member and fall thence into the buckets on the down stream side, said bridge mechanism including a girder built into the buttresses and extending horizontally across the space between the buttresses adjacent to and above the up stream side of the rotating member and also including a plurality of parallel stringers supported at one end on said girder, and a suitable water tight floor resting on said stringers.

3. In a device of the character set forth, the combination of a pair of spaced parallel concrete buttresses having bearing members built therein, a rotating member journaled in said bearing members and substantially of a length filling the space between the buttresses, the rotating member being of unitary structure and comprising rigid blades or buckets upwardly curved on the down stream side of the axis thereof, and bridge mechanism serving to cause the water to flow in a continuous stream over the top of the rotating member and fall thence into the buckets on the down stream side, said bridge mechanism including a girder built into the buttresses and extending horizontally across the space between the buttresses adjacent to and above the up stream side of the rotating member and also including a plurality of parallel stringers supported at one end on said girder and a series of closely fitted planks extending transversely across and supported upon said stringers.

4. In a water power device, the combina-

tion of a rotating member, a pair of buttresses in which the rotary member is journaled, the rotating member being substantially coincident in length with the space between the buttresses and having buckets arranged parallel to its axis, retaining walls extending up stream from the buttresses and constituting continuations thereof, a girder built into the buttresses and extending across the space between the buttresses on about the level of the top of the rotating member and on the up stream side thereof, said girder having formed along its up stream edge with a rabbet, a series of stringers having one end set into said rabbet and extending thence up stream and resting at their ends on the bottom of the stream, and a plurality of planks extending transversely across and fixed upon said stringers filling the space between the girder and the bottom of the stream.

5. A device as set forth in claim 4 in which a vertically adjustable coping member is provided having one edge supported adjacent to the uppermost plank at the top of the girder and extending thence over and adjacent to the top of the rotary member, means being provided to support the free edge of the coping member at any desired elevation with respect to the rotary member.

In testimony whereof I affix my signature.

WILLIAM ADELMANN.
